(57) **CLAIM**

The ornamental design for an air freshener gel dispenser, as shown and described.

DESCRIPTION

FIG. 1 is a right front perspective view of an air freshener gel dispenser showing the invention;

FIG. 2 is a front elevational view of the air freshener gel dispenser of FIG. 1, wherein the left side elevational view, rear elevational view and right side elevational views are identical thereto;

FIG. 3 is a top plan view of the air freshener gel dispenser of FIG. 1;

FIG. 4 is a bottom plan view of the air freshener gel dispenser of FIG. 1;

FIG. 5 is a right front perspective view of an air freshener gel dispenser showing an alternative embodiment of the invention;

FIG. 6 is a front elevational view of the air freshener gel dispenser of FIG. 5, wherein the left side elevational view, rear elevational view and right side elevational views are identical thereto;

FIG. 7 is a top plan view of the air freshener gel dispenser of FIG. 5; and,

FIG. 8 is a bottom plan view of the air freshener gel dispenser of FIG. 5.

The broken lines in FIGS. 5-8 are for illustrative purposes only and form no part of the claimed design.
